The ornamental design for a height adjustment means
for selective spacing between circular cooking grill and
hanging fire grate, as shown and described.

[21] Appl. No.: **963,455**

DESCRIPTION

[22] Filed: **Nov. 24, 1978**

FIG. 1 is an environmental perspective view of a height
adjustment means for selective spacing between circular
cooking grill and hanging fire grate showing my
new design;

FIG. 2 is a top plan view;

FIG. 3 is a bottom plan view;

FIG. 4 is an interior side elevational view;

FIG. 5 is a side elevational view opposite FIG. 4;

FIG. 6 is an end elevational view of which the opposite
side is a mirror image.

The broken line disclosure of a grill and fire grate in
FIG. 1 is for illustrative purposes only and forms no
part of the claimed design.
